UNITED STATES PATENT OFFICE.

FREDERICK J. SCHMIDT, OF STEELTON, PENNSYLVANIA.

FLASH-LIGHT ATTACHMENT.

Application filed September 25, 1922. Serial No. 590,460.

To all whom it may concern:

Be it known that I, FREDERICK J. SCHMIDT, a citizen of the United States, residing at Steelton, in the county of Dauphin and 5 State of Pennsylvania, have invented certain new and useful Improvements in Flash-Light Attachments, of which the following is a specification.

The present invention appertains to improvements in electrical testing apparatus of 10 a type designed especially as an attachment unit for flashlights. The primary object in view is to provide a simple device by means of which circuit testing may readily be carried out, employing the light of the flashlight device as the indicating means, one of 15 the essential features of my invention residing in the arrangement of a compact detachable section for attachment to the conventional constructions of flashlights without requirement of modification.

The invention is characterized as to novelty by the provision of a shell or case, a cord unit removably connected thereto and 25 a circuit closing clip by means of which to establish a closed circuit through the attachment when the flashlight is to be used in the usual manner.

These and such other objects as may hereinafter appear are attained by the novel construction, combination and arrangement 30 of parts to be hereinafter specifically described and claimed.

Reference will now be had to the accompanying drawing forming a part of this specification, wherein:

Fig. 1 is a side elevation of a device embodying my invention, the attachment unit being shown in section, and the flexible conductor in extended position.

Fig. 2 is a sectional view of the attachment unit alone, showing the cord in nested position within the shell.

Fig. 3 is a horizontal sectional view 45 through the unit below the socket support.

Figs. 4 and 5 are side and top plan views, respectively of the circuit closing clip used with the attachment; and

Fig. 6 is a perspective view of the end of 50 the cord unit with the clip in circuit closing position on the testing terminals.

Throughout the following detailed de-

scription and on the several figures of the drawing, similar parts are referred to by like reference characters.

Referring to the drawing, 1 indicates the body portion or casing of a conventional type of flashlight, in which is housed a battery 2, the customary closing cap for the end being removed and utilized as the closure 60 for the attachment, as indicated at 3.

The unit forming the special subject-matter of this invention is connected to the end of the case 1 in place of the cap, as shown in Fig. 1. This unit comprises a tubular shell 4 formed with threads at each end so

as to screw upon the end of the casing 1 and receive the cap 3, as aforesaid. Within the shell is a cross support 5 formed centrally with a socket 6 in which is removably introduced the screw cap plug 7. One of the electric terminals of this plug, designated 8, when in position contacts with segment 9

partly closing the opening 10 through the support 5, the other terminal 11 being prolonged so as to pass through the opening into contact with the battery 2. These terminals are, as usual, spring actuated or yieldable and to the plug is connected a double flexible extension cord 12, or any sim-

ilar dual cable, each wire of which has connected thereto at its end a testing terminal 13. Each of these members carries a crew 14 for attaching the wire and is formed with a headed extremity 15. The extension

cord 12 may be of any desired length, but is preferably no longer than will be readily accommodated by the shell 4 within which it is designed to be nested by winding it around the plug 7 when not in use, for testing purposes, as shown in Figs. 1 and 2.

Removal of the cap 3 from the unit enables the cord to be pulled out and by applying the testing terminals to the points of an electric circuit suspected of containing a short or break, and closing the regular switch 16, the circuit will be closed through

the light if not broken between the testing terminals. By means of this device fuses, light bulbs, armature windings and many other electrical articles may be tested for

grounds or breaks.

When not in use and in order to maintain the flashlight operative as usual, I prefer to

- employ a closing clip 17, as shown in Figs. 4 and 5, so formed as to slidably engage with the headed extremities of the testing terminals 13, as shown most clearly in Fig. 6. This holds the two clasped tightly between its spring jaws and maintains the circuit closed through the extension cord, ready to be completed by the manipulation of the switch 16.
- 10 It is obvious that the provision of a separable cord unit for the attachment enables this element to be readily displaced for insertion of a longer cord, if desired, replacement of worn conductors, or for other purposes. Owing to the compactness of the device it may readily be carried in the

pocket or form a part of automobile equipment.

Having thus described my invention, what I claim as new is:

20 A shell having an enclosing support formed with a fixed central socket and an opening at its base and an extension cord unit adapted to be stored in the space surrounding said socket and having a plug one 25 terminal of which contacts with the socket and the other terminal passing through said opening for contact with a flashlight battery.

25 In testimony whereof I affix my signature.

FREDERICK J. SCHMIDT.
